UNITED STATES PATENT OFFICE.

RUFUS B. CARR, OF BOSTON, MASSACHUSETTS, ASSIGNOR OF ONE-HALF TO
THE E. HOWARD WATCH AND CLOCK COMPANY, OF SAME PLACE.

DESIGN FOR TIME-PIECE CHARACTERS.

SPECIFICATION forming part of Design No. 18,488, dated July 31, 1888.

Application filed March 5, 1888. Serial No. 266,216. Term of patent 14 years.

To all whom it may concern:

Be it known that I, RUFUS B. CARR, of Boston, in the county of Suffolk and State of Massachusetts, have invented a new and original Design for a Series of Time-Piece Characters, of which the following is a specification.

My design has reference to time-piece dials; and it consists, as set forth in the accompanying drawing, of a surface configuration of a series of characters, *a*, arranged at uniform distances apart and in circular order on a time piece dial, a character, *b*, which is a single mark or dot having pointed corners, placed near one of the characters *a* and nearer the center of the dial, and a series of twelve characters, *c*, which are single marks or dots of uniform size and shape, placed at uniform distances apart and in circular order, the series of characters *c* being concentric with the series of characters *a*. The characters thus formed and arranged give a symmetrical and pleasing effect to a twenty-four-hour dial by relieving its surface of a crowded or overloaded appearance.

The leading feature of my design is com-

prised in the dial-surface configuration of a series of characters, *a*, the single character *b*, having pointed corners, and the series of characters *c*.

I claim—

The design for a time dial, as shown and described, the same consisting of the surface configuration of a series of characters, *a*, arranged in circular order and at uniform distances apart on said dial, the single character *b*, having pointed corners, located between one of the characters *a* and the center of the dial, and the series of characters *c*, concentric with the characters *a* and arranged between the latter and the margin of the dial, as specified.

In testimony whereof I have signed my name to this specification, in the presence of two subscribing witnesses, this 1st day of March, A. A. 1888.

RUFUS B. CARR.
